United States Patent Office

Des. 197,078
Patented Dec. 10, 1963

197,078

CLOCK

Charles A. McLeod, Evanston, Ill., assignor to Sunbeam Corporation, Chicago, Ill., a corporation of Illinois

Filed July 11, 1963, Ser. No. 75,745

Term of patent 14 years

(Cl. D42—7)

Fig. 2.

FIG. 1 is a front elevational view of a clock showing my new design;

FIG. 2 is a top plan view thereof;

FIG. 3 is an enlarged sectional view taken along the section line 3—3 of FIG. 1;

FIG. 4 is an enlarged sectional view taken along the section line 4—4 of FIG. 1; and

FIG. 5 is an enlarged sectional view taken along the section line 5—5 of FIG. 1.

I claim:

The ornamental design of a clock, as shown.
